(57) **CLAIM**

The ornamental design for an air compressor for a vehicle, as shown and described.

DESCRIPTION

FIG. 1 is a front left elevated perspective view of an air compressor for a vehicle according to the present invention. FIG. 2 is a front right elevated perspective view of the air compressor shown in FIG. 1.

FIG. 3 is a front right perspective view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

The broken line showing of air compressor for a vehicle is included for the purpose of illustrating portions of the article and forms no part of the claimed design.

1 Claim, 10 Drawing Sheets
